UNITED STATES PATENT OFFICE

JOHN F. KLEIN, OF BELLEVILLE, ILLINOIS, ASSIGNOR TO KNAPP-MONARCH COMPANY,
OF BELLEVILLE, ILLINOIS, A CORPORATION OF MISSOURI

DESIGN FOR A WAFFLE IRON

Application filed December 21, 1931. Serial No. 42,165. Term of patent 7 years.

To all whom it may concern:

Be it known that I, JOHN F. KLEIN, a citizen of the United States, and a resident of Belleville, in the county of St. Clair and State of Illinois, have invented a certain new, original, and ornamental Design for a Waffle Iron, of which the following is a specification, reference being had to the accompanying drawings, forming part thereof.

Figure 1 is a plan view of a waffle iron illustrating my new design.

Figure 2 is a front elevation of the waffle iron; and

Figure 3 is a side elevation thereof.

I claim:

The ornamental design for a waffle iron substantially as shown.

Des Moines, Iowa, December 10, 1931.

JOHN F. KLEIN.
